United States Patent Office.

JOHN H. BROMLEY, OF PHILADELPHIA, PENNSYLVANIA, ASSIGNOR TO JOHN BROMLEY & SONS, OF SAME PLACE.

Design No. 4,624, dated February 7, 1871.

DESIGN FOR A CARPET-PATTERN.

The Schedule referred to in these Letters Patent and making part of the same.

to all whom it may concern:

Be it known that I, JOHN H. BROMLEY, of the City and county of Philadelphia and State of Pennsylvania, have invented and produced a new and original Design for Carpets, of which the following is specification.

The nature of my design is fully represented in the accompanying photographic illustration, to which reference is made.

I claim as my invention—

The design for a carpet, as shown.

Witnesses:

JOHN H. BROMLEY.
